INVENTOR.

BY *Robert W. Nangle*

ATTORNEY.

UNITED STATES PATENT OFFICE.

WILLIAM M. McNEIL, OF PORTLAND, INDIANA.

TANK-FORMING DEVICE.

SPECIFICATION forming part of Letters Patent No. 760,911, dated May 24, 1904.

Application filed September 21, 1903. Serial No. 173,990. (No model.)

To all whom it may concern:

Be it known that I, WILLIAM M. McNEIL, a citizen of the United States, residing in the city of Portland, in the county of Jay, and in the State of Indiana, have made new and useful Improvements in Tank-Forming Devices, of which the following is a detail exposition of the mechanical construction of the essential requisites thereof, followed by a lucid statement of its intended operation, whereby others may construct and operate the same by reference to the accompanying drawings, forming a part of this specification.

This invention relates more particularly to the construction and arrangement of a device for forming tanks or the like above the surface of the ground where the tank is to be formed of a plastic material, such as cement, and where both the outside and inside wall is to be formed by mechanical means.

The object I have in view is to provide a separable two-part device of different dimensions circumferentially, whereby a space is formed between the two parts of a width the same as the predetermined thickness of the wall of the tank or the like to be formed thereby.

Another object of my invention is to provide a tank-forming device composed of a combination of tested and simple mechanical instrumentalities arranged to produce the highest measure of efficiency and that with a material reduction in expense and in manual operations.

Another object is to provide a device for the purpose stated by the aid of which cement tanks or the like may be formed expeditiously and easily, to provide means for assembling the various parts positively, and for as easily removing the various parts after the material of the tank or the like has sufficiently hardened and stonified; and still another object is to generally improve and simplify the construction and operation of devices of this general character.

Other specific objects and advantages of my invention will be apparent from the following detail description and from an inspection of the accompanying drawings, forming a part thereof.

The invention consists in the construction and arrangement of the several essential elements, together with the form and disposition of the various details and the manner of their assembly.

With the above-named objects in view I will now take up the detail description of the invention, which I will endeavor to place in such clear and concise terms that its construction may not be misunderstood or that its intended operation may not be misconstrued.

Referring now to the drawings, Figure 1 represents a central vertical section of my assembled mechanism, taken on the line Y Y of Fig. 2, showing both the inside and the outside tiers of sections. Fig. 2 is a central horizontal section of my assembled mechanism, taken on the line X X of Fig. 1, and also showing both the inside and the outside tiers of sections. Fig. 3 is an isometrical detail of a portion of my mechanism, showing the construction of the sections in detail and the relative positions of the various parts. Fig. 4 is an isometrical detail view of the last sections to be adjusted in position, showing the manner of connecting the same. Fig. 5 is a detail elevation of a portion of the outside of the outer tiers, illustrating the manner of connecting the last-inserted stays.

Similar reference characters denote like parts throughout the several views.

My improvements herein shown and described are intended primarily for use in forming cement tanks or the like above the surface of the ground. However, it will be apparent that at least some of the parts will be applicable in connection with "cistern-forming devices," as specifically described and claimed in my application relating thereto filed simultaneously herewith and bearing same date thereof and serial number next thereto.

This present construction consists, essentially, of two tiers of sections of different circumference set up vertically in circular form with a space therebetween, as shown. The sections of the inside tier are each formed of an oblong metal plate A, with a rib B secured to and extending along one of its longer sides and cross-ribs C extending across the top and bottom of the inside of the plate A and se-

cured thereto and extending from the rib B to near the opposite edge of the plate A, leaving the edge of the plate A opposite the rib B a tongue to overlap the edge of the adjoining plate when the device is assembled. Near the free end of the inside face of the rib C is a staple 1, loosely securing the elongated link 2, and near the opposite end of each rib C is a pivotal L-shaped dog 3, adapted to be removed, but not removed. When two of the sections are brought together, as in Figs. 1 and 2, the dog 3 may be turned to point toward the staple 1, and the link 2 of the opposite section may then be placed over the shank 15 of the dog 3, and the dog is then turned in the opposite direction, as in Fig. 1, which will lock the two adjoining sections together, as shown.

Secured to the inner faces central of the 20 upper and lower ribs C, parallel with the rib B, is a brace D, the center of which is deflected to touch the plate A of that section, where it is secured by a rivet or the like, the ends of the brace being secured to said upper and 25 lower ribs C in like manner, as shown.

To provide means for disassembling the sections after their work has been accomplished, I provide the adjoining edges of two of the sections somewhat different from the others 30 by the employment of the construction shown most clearly in Fig. 4 and is described as follows: In the end of the rib of one of said sections is a dowel-pin 4, and in the opposite section the rib C is formed shorter than in the 35 other sections. A bolt 5 projects through the rib C near said shorter end, with a nut 6 operating thereon. The index E denotes an angular iron having a long portion with a slot 7 disposed longitudinally therethrough and 40 with a relatively shorter end bent at right angles to the longer end, with a hole therethrough to receive said pin 4. By the above it will be seen that after the other sections have been positioned the two modified sections 45 may be positioned with the metal plate A of the section carrying said angle-iron overlapping the metal portion A of the opposite section having the dowel-pin, by which construction it is apparent that the disparity 50 between the meeting of the said two sections may be taken up by moving the angle-iron E toward said opposite section, entering the pin 4 in the hole in the angle-iron, as shown, and then by tightening the nut 6 the 55 sections are prevented from being pressed inward from without.

The outer tier of sections are similar in construction to those above described except that their curvature is in the opposite direction 60 thereto—that is to say, the faces of the inner tier of sections are concave, while the faces of the outer tier of sections are convex, with the faces of the latter opposite to, parallel with, and disposed some distance apart from the former, 65 as shown. Consequently the circumference

of the outer tier is somewhat greater than that of the inner tier. The outer sections are composed of a plate F, having cross-ribs G, and with the link connections for each section similar in construction to the above-described 70 link connection on the inside sections except that with the outside section the link connections are on the outside. In the case of the last outside sections they are similarly formed to the above-described last two of the inside 75 sections except that a plate H is provided in place of the angle-iron, which plate is bolted at one end by the bolt 8 near the edge of one section and extends out over the opposite section with a longitudinal slot 9 therethrough 80 to receive the bolt 10, which latter is secured in the cross-rib of the said opposite section and with a nut 11 on said bolt to secure said plate H at desired points, as in Fig. 5.

When constructed as stated, the two tiers 85 of sections are then set up in the manner shown with a space between their faces of a width the same as the predetermined thickness of the wall to be formed thereby and are secured to the earth at the bottom as follows: 90 Vertically through both top and bottom cross-ribs C and G are holes, as shown, the lower holes being adapted to receive the pins I, which are to be driven therethrough into the earth or whatever the tank to be formed is 95 to rest on. In order to space the two tiers of sections and retain them the proper distance apart, I provide a number of plates K with holes therethrough along their lengths, as shown in Fig. 3. Said plates are to be laid 100 on the upper ends of the sections across from the inner to the outer tier of sections, and pins 12 are to be inserted through said soles in the plates K and thence into the corresponding holes in upper cross-ribs C and G, 105 above referred to, as shown in Fig. 3. After the device has been set up and assembled, as shown and described, the space between the sections may be filled in with the plastic or de-liquidous cement and allowed to harden there- 110 in, after which the various parts may be dis- 115 assembled and removed and a bottom formed in the tank of same material as said walls, and thus accomplishing the objects of this invention.

In the accompanying drawings I have shown the construction to contain only eight sections in each tier simply as a matter of convenience, whereas in actual practice a greater number of sections may be employed, if desired, in 120 order to attain the desired circumference and at the same time making the sections easy to handle and transport.

From the above description, taken in connection with the accompanying drawings, it 125 will be apparent that I have produced an improved tank-forming device embodying the objects elsewhere referred to in this specification and shown in the accompanying drawings. 130

While I have illustrated and described the best means now known to me for carrying out the objects of my invention, I desire it to be understood that I do not restrict myself to the exact details of the construction shown and described, but hold that any slight changes or variations therein as would suggest themselves to the ordinary mechanic would clearly fall within the limit and scope of my invention.

Having now fully shown and described my invention and the best means for its construction to me known at this time, what I claim, and desire to secure by Letters Patent of the United States, is—

1. A tank-forming device comprising in combination, an inner tier of separable sections, an outer tier of separable sections some distance from the said inner tier and parallel therewith, said sections of the inner tier being formed of an oblong plate, ribs secured to and extending along one of the sides of the plate, cross-ribs extending across the top and bottom of each plate from said side rib to near the opposite edge of each plate whereby a tongue is formed of one edge of each plate to overlap the edge of the adjoining plate, staples secured in the inner face of the cross-ribs, an elongated link carried by each of said staples, a pivotal L-shaped dog mounted on the opposite ends of the outer face of the cross-ribs and adapted to enter the link of the opposite section to lock the sections together, means for connecting the last two sections to be assembled, means for disassembling the sections after their work is completed, means for connecting the two tiers of sections at the top, and means for securing all of the sections at the bottom, all substantially as shown and described.

2. A tank-forming device comprising in combination, an outer tier of separable sections, an inner tier of separable sections with a space between the two tiers of sections, said sections of the outer tier being formed each

of an oblong plate, a rib secured to and extending along one of the sides of each plate, cross-ribs extending across the top and bottom of each plate from said side rib to near the opposite edge of each plate whereby a tongue is formed of one edge of each plate to overlap the edge of the adjoining plate, staples secured in the outer face of the cross-ribs, an elongated link carried by each of said staples, a pivotal L-shaped dog mounted on the opposite ends of the outer face of the cross-ribs and adapted to enter the link of the opposite section to lock the sections together, means for connecting the last two sections to be assembled, means for disassembling the sections after their work is completed, means for connecting the two tiers of sections at the top, and means for securing all of the sections at the bottom, all substantially as shown and described.

3. A tank-forming device comprising in combination, an outer and an inner tier of separable sections, said sections being formed of oblong curved plates, each of the sections of the inner tier having a rib secured along one side and across each end and on the concave side of the sections, means for securing said inner sections together in a circle, each of the sections of the outer tier having a rib secured along one side and across each end on the convex side of the sections, means for securing said outer sections together in a circle, the lower cross-ribs of both the inner and outer sections having vertical holes therethrough, pins for insertion through said holes for the purpose set forth, and plates for locking the tiers a determined distance apart, all substantially as shown and described.

In testimony whereof I have hereunto signed my name to this specification in the presence of two subscribing witnesses.

WILLIAM M. McNEIL.
